LOADING PLATFORM

William H. Rambo, Portland, Oreg.

Application July 16, 1945, Serial No. 605,354

7 Claims. (Cl. 214—126)

1

The present invention relates to loading platforms and while it is not necessarily limited thereto, it is particularly adaptable for use in connection with elevators.

More specifically the invention relates to a loading platform arrangement upon which a load may be placed in readiness to be transported to another location by a carrier and which is operative for automatically transferring such load onto the carrier as the carrier is moved into a predetermined position adjacent the loading platform.

A further object of the present invention is to provide a new and novel loading platform arrangement adapted for holding a load contained upon a suitable vehicle, the loading platform being further adapted to be tilted for causing transfer of said vehicle onto said carrier.

A still further object of the present invention is to provide a new and improved loading platform arrangement adapted for holding thereupon a load contained upon a suitable vehicle, the platform being adapted to be tilted in response to the movement of a carrier to a predetermined position adjacent thereto for effecting transfer of the load containing vehicle from the platform onto the carrier, the platform being automatically restored to normal position upon movement of the carrier away from the platform.

Further objects and advantages of the invention will appear from the following description taken in connection with the accompanying drawing while the features of novelty characterizing the invention will be pointed out with greater particularity in the appended claims.

In the drawings Fig. 1 is a longitudinal sectional elevation through an elevator and loading platform arrangement therefor constructed in accordance with one form of the present invention and taken along the line 1—1 of Fig. 2; Fig. 2 is a cross-sectional view taken along the line 2—2 of Fig. 1; and Fig. 3 is an enlarged sectional view illustrating certain details of the invention.

The loading platform arrangement of the present invention will be described as it may be adapted for automatically transferring loads onto an elevator. It will readily be understood by those skilled in the art that the invention is not to be necessarily so limited in that it is equally applicable for effecting transfer of loads onto other forms of load carriers.

The elevator in this instance is shown as comprising a platform or floor 10 arranged for vertical movement within the parallel upright guides

2

11 arranged at the four corners thereof. The elevator platform may be raised and lowered by any suitable means such as the cables 12 connected to the hoist drums 13 and which may in turn be controlled by the driving motor 14. The elevator platform 10 shown in its lowermost position is adapted to be supported upon bumper blocks 15. The elevator in this instance is designed particularly for raising loads to an elevated level from which the loads are removed, but since the unloading means forms no part of the present invention, such details have been omitted from the drawing for purposes of greater clarity. As shown in the drawing, the platform 10 of the elevator is provided with a pair of parallel spaced apart tracks 16 upon which a vehicle containing a load is to be carried though it will be understood that such tracks are not essential.

Mounted adjacent the elevator is a loading platform indicated at 20 and which is hingedly supported as at 21 at its end remote from the elevator. The end of the platform adjacent the elevator is adapted to be supported by a collapsible bracket means which is illustrated more clearly in the enlarged detail view of Fig. 3. The bracket means comprises a pair of hinged toggle links 22 and 23 which are connected at one end as at 24 to the underneath side of the loading platform framework while the lower end thereof is pivotally mounted in a suitable bearing support 25 resting upon the foundation therebeneath. In the straightened condition of the toggle links 22 and 23 as shown in Fig. 3 the forward end of the loading platform 20 is retained in an upper position such that the top of the loading platform is substantially horizontal, the horizontal position being indicated by dotted lines 26 in Fig. 1. In the straightened condition the two links extend in a slightly overcenter condition, the connection between the two links resting against a suitable backing support 27.

Attached to the lowermost toggle link 23 is an operating lever arm 28 which extends angularly outwardly into the path of travel of operating means 29 therefor attached to the elevator platform 10. The operating means 29 includes a trip plate 31 which is adapted to engage the outermost end of the lever 28 as the platform 10 of the elevator moves past the adjacent edge of the loading platform 20 supported in the horizontal position. Upon slight continued downward movement of the elevator, the lever 28 is rocked about the pivot 25 so that the toggle links 22, 23 are carried past the overcenter position whereupon they will collapse and drop the corresponding end of the

loading platform 20 to the tilted position shown in full line in Fig. 1. The forward end of the loading platform 20 is supported in its lowermost or tilted position upon wooden bumper blocks indicated at 30 mounted upon the foundation. In this position, the end of the loading platform is even with the top of the elevator floor when the elevator is resting upon the bumper blocks 15.

The loading platform 20, in this instance, is also provided with a pair of parallel spaced apart tracks 32 for supporting load carrying vehicles such as indicated by dotted lines 33. It will be obvious that with the loading platform supported in the horizontal position a loaded vehicle, such as 33, may be rolled out thereupon at such time as it may be convenient, for example, while the elevator platform 10 is in an uppermost position and being unloaded. For preventing rolling of the loaded vehicle from the end of the loading platform 20 an automatic stop is provided consisting of a pivoted lever 35 one end of which is connected by a link 36 to a bracket 37 fixedly attached to the foundation. The opposite end of the lever 35 is provided with a stop 38. In the raised position of the loading platform 20 the lever 35 is caused to rotate about its pivot in the clockwise direction and the stop 38 projected into the path of travel of the foremost wheel of the load supporting vehicle 33 thereby arresting continued forward movement thereof. As the toggle link supporting bracket for the forward end of the loading platform 20 is collapsed and the loading platform 20 dropped to its tilted position the lever 35 is rotated to the out-of-way position shown in full line in Fig. 1 whereupon the loaded vehicle 33 is permitted to roll by gravity down the inclined tracks 32 onto the tracks 16 on the elevator carriage. A suitable bumper means indicated at 40 may be provided on the opposite end of the elevator platform to arrest the movement of the vehicle thereupon.

With the loaded vehicle thus transferred onto the elevator platform the elevator may thereupon be raised to a desired upper level and whereupon the loading platform 20 will automatically be restored to its normal horizontal position. With further reference to Fig. 3 it will be observed that upon collapsing movement of the toggle links 22, 23 past the overcenter position, the operating lever 28 is swung downwardly into engagement with the sloping plate 42 mounted beneath the tripping member 31. Upon upward movement of the elevator carriage 10 the plate 42 will carry the outer end of the operating lever 28 upwardly to a position just slightly past the overcenter position whereupon it will move a slightly distance further until the hinge connection between the toggle links 22, 23 come to rest against the backing support 21. In this position, the outermost end of the lever arm 28 will be clear of the lowermost end of the sloping resetting plate 42 so that it may readily move upwardly therepast and also so that in the subsequent downward movement of the elevator the lever arm 28 will not be engaged by the plate 42 until after the lever is tripped by the plate 31. The plates 31 and 42 may be mounted in any suitable manner upon the elevator platform 10. As shown in the drawings these plates 31 and 42 are rigidly secured between a pair of spaced apart plates 44 and which are secured at their upper ends to the underneath side of the elevator platform 10 on its end next adjacent the loading platform. It will furthermore be understood that two such toggle link supporting bracket means

will ordinarily be provided for the loading platform 20, one adjacent each of the opposite sides thereof. It will also be obvious that while the collapsible supporting means is shown in this instance as comprising an overcenter toggle linkage any other suitable supporting means is represented thereby which is adapted for supporting the loading platform in a horizontal position for having a loaded vehicle moved thereupon and for dropping the end of the loading platform to a cooperatively adjacent position.

It will also be obvious that while the invention has been described with particular regard for effecting loading of the elevator in its lowermost position the loading platform arrangement may be readily adapted for effecting automatic loading of the elevator at any point in its travel or at its uppermost position.

Having described the invention in what is considered to be a preferred embodiment thereof it is desired that it be understood that the specific details shown are merely illustrative and that the invention may be carried out by other means.

What I claim is:

1. In an elevator loading apparatus, the combination comprising an elevator having a floor including a pair of spaced apart vehicle tracks thereupon, a loading platform provided adjacent said elevator including a pair of spaced apart vehicle tracks thereupon, said loading platform being pivotally mounted at the end remote from said elevator, a collapsible bracket means connected to the end of said loading platform adjacent said elevator, said bracket means in the operative position supporting said loading platform in a substantially horizontal position, said bracket means in the collapsed condition permitting downward movement of the end of said loading platform adjacent said elevator to a lower limit position, an operating lever operatively connected to said bracket means, means secured to said elevator in one direction for causing collapse of said bracket means, means for arresting movement of said elevator in said one direction in a position corresponding with the lowered position of said loading platform whereby a vehicle supported on the tracks of said loading platform is permitted to roll therefrom onto said tracks on said elevator, and means on said elevator operatively engaging with said lever upon movement of said elevator in the opposite direction for restoring said bracket means to the operative position and said loading platform to the horizontal condition.
2. In an elevator loading apparatus the combination comprising an elevator, a loading platform mounted adjacent said elevator, said loading platform being hingedly mounted at its end remote from said elevator, a collapsible support for supporting the end of said loading platform adjacent said elevator in an upward substantially horizontal position, a firm foundation for one end of said support whereby said support in the extended condition thereof rigidly supports said loading platform in said substantially horizontal position, and means on said elevator operative upon movement of said elevator downwardly past said loading platform for engaging and effecting collapse of said collapsible support and tilting of said loading platform whereby vehicles positioned on said loading platform are caused to roll by gravity therefrom onto said elevator.
3. In an elevator loading apparatus the combination comprising an elevator including a floor, a loading platform rockably mounted adjacent

said elevator, collapsible bracket means for restraining said loading platform in a substantially horizontal position, a firm foundation for one end of said bracket means whereby said bracket means in the extended condition thereof rigidly supports said loading platform in said substantially horizontal position, and means responsive to movement of said elevator floor past said loading platform for engaging and causing release of said bracket restraining means whereby said platform is permitted to rock downwardly toward said floor causing vehicles positioned on said platform to roll therefrom onto said elevator.

4. In an elevator loading apparatus the combination comprising an elevator including a floor, a loading platform mounted adjacent the path of travel of said floor, means pivotally supporting said platform for tilting movement between a substantially horizontal position and a position sloping downwardly toward said floor, toggle linkage means for supporting said loading platform in said horizontal position, means responsive to movement of said elevator floor in one direction past said loading platform for engaging and tripping said supporting toggle linkage and causing tilting of said loading platform, and means responsive to movement of said floor in the opposite direction for restoring said toggle linkage to normal position for supporting said loading platform in said horizontal position.

5. An elevator loading apparatus comprising the combination of a load receiver, a load holder mounted cooperatively adjacent the path of travel of said receiver, means normally supporting said load holder in a substantially horizontal position, means responsive to movement of said load receiver in one direction to a predetermined position adjacent said load holder for effecting tilting of said load holder toward said load receiver for transferring load from said holder onto said receiver, and means on said load receiver responsive to movement of said receiver in the opposite direction for engaging said supporting means and restoring said load holder to said horizontal position.

6. In an elevator loading apparatus the combination comprising an elevator including a load receiver, a load holder pivotally mounted adjacent the path of travel of said load receiver, means for releasably supporting said load holder in a

substantially horizontal position, said supporting means comprising an overcenter toggle linkage, means secured relatively to said load receiver for operatively engaging said toggle linkage for effecting the collapse thereof upon movement of said loading receiver past said load holder in one direction and means on said load receiver for operatively engaging and restoring said toggle linkage to the straightened condition for supporting said load holder in the horizontal position.

7. A loading platform arrangement comprising the combination of a platform adapted for holding a wheeled vehicle, means mounting said loading platform for rocking movement in the longitudinal direction, supporting means operatively connected to said platform for normally holding said platform in a substantially horizontal position, a pivoted lever on said platform for limiting forward movement of a wheeled vehicle thereupon, a carrier, actuating means on said carrier for engaging said supporting means as said carrier is moved adjacent said platform, said actuating means causing release of said supporting means to permit forward tilting of said loading platform, a link connected between said lever and a fixed support for automatically shifting said lever to an inoperative position upon tilting of said platform, said actuating means including means for restoring said supporting means to the normal horizontal position of said platform upon movement of said carrier away from said platform, said lever being automatically shifted to an operative position upon movement of said platform to said normal horizontal position.
